UNITED STATES PATENT OFFICE.

JOSEPHUS HOOPER, OF LOUISVILLE, KENTUCKY; THE COLUMBIA FINANCE & TRUST CO., ADMINISTRATOR OF SAID HOOPER, DECEASED, ASSIGNOR OF ONE-HALF TO CURRAN POPE, OF SAME PLACE.

DESIGN FOR A MOUTHPIECE FOR PREVENTION OF MOUTH-BREATHING.

SPECIFICATION forming part of Design No. 32,565, dated April 24, 1900.

Application filed December 1, 1899. Serial No. 738,925. Term of patent 14 years.

To all whom it may concern:

Be it known that I, JOSEPHUS HOOPER, a citizen of the United States, and a resident of Louisville, in the county of Jefferson and State 5 of Kentucky, have invented and produced a certain new and useful Design for Mouth-pieces for Prevention of Mouth-Breathing; and I do hereby declare that the following is such a full, clear, and exact description of the 10 same as will enable others skilled in the art to which the invention relates to make and use the same, reference being had to the accompanying drawings, forming part of this specification.

15 In the drawings, Figure 1 is a perspective view of the device looking from the rear side. Fig. 2 is a vertical cross-section through the center of the same. Fig. 3 is a horizontal longitudinal section taken at right angles to 20 the line of section of Fig. 2.

The device consists of a thin soft flexible membrane or diaphragm made of some material impervious to air and moisture and intended to be placed between the lips and the 25 front teeth of such persons as have the habit of breathing through the mouth. It is molded or shaped to conform to the general outline of the gums and teeth, and consists of an approximately-oval piece of the described ma-

terial which is curved in the direction of its 30 length, as best shown in Fig. 3, and in the direction of its width, as represented in Fig. 2.

Referring again to the views of the drawings, A indicates the device as a whole, and a' denotes the membrane or diaphragm 35 composing it. As shown in the sectional views Figs. 2 and 3, this diaphragm is thinner toward the edges than in the middle, and its ends are narrower than the body portion by reason of the curvilinear formation of the top 40 and bottom edges of said ends, as clearly illustrated in Figs. 1 and 2.

The letter d' indicates a projection extending outward from the front central portion of the same and forming a convenient point of 45 attachment for a string which may be secured to the person or clothes of the wearer.

Having thus described my invention, what I claim is--

The design for mouthpieces for prevention of mouth-breathing herein shown and described.

In testimony whereof I affix my signature in presence of two witnesses.

JOSEPHUS HOOPER.
